The ornamental design for a transitional image for liquid crystal display panel for forklift truck, as shown and described.

DESCRIPTION

FIG. 1 is a front view of first image of a transitional image for liquid crystal display panel for forklift truck showing our new design:

FIG. 2 is a rear view thereof;

FIG. 3 is a left side view thereof;

FIG. 4 is a right side view thereof;

FIG. 5 is a top (plan) view thereof;

FIG. 6 is a bottom view thereof;

FIG. 7 is a front view of a second image of a transitional image for liquid crystal display panel for forklift truck showing our new design; and,

FIG. 8 is a front view of a third image of a transitional image for liquid crystal display panel for forklift truck showing our new design.

The broken line showing of a display panel is included for the purpose of illustrating the environmental structure and forms no part of the claimed design.

The appearance of the transitional image sequentially transitions between the images shown in FIGS. 1, 7 and 8. This process or period forms no part of the claimed design.
